UNITED STATES PATENT OFFICE

WALTER D. SHAFFER, OF CHICAGO, ILLINOIS, ASSIGNOR TO UNITED SHOE MACHINERY CORPORATION, OF PATERSON, NEW JERSEY, A CORPORATION OF NEW JERSEY

STOCK-FITTING MACHINE

Application filed April 28, 1924. Serial No. 709,465.

This invention relates to improvements in sole fitting machines. The invention is herein illustrated as embodied in a machine for turning up and setting the lips of double-lipped insole blanks such as are used in making which is known as Economy insoles.

An example of a double-lipped insole of the Economy type may be found in United States Letters Patent No. 849,245, granted April 2, 1907, upon application of A. E. Johnson. The insole described in this patent comprises a body portion of leather having inner and outer channels cut therein so as to form, at one side of the insole, inner and outer channel flaps or lips which are adapted to be turned outwardly from the body of the insole and secured together under pressure by means of cement to provide an upstanding sewing rib adapted to be covered by reinforcing fabric.

United States Letters Patent No. 1,213,770, granted January 23, 1917, upon application of A. E. Johnson, discloses a machine of a type heretofore commonly employed for setting the lips of double-lipped Economy insole blanks. In machines of the type just referred to, cooperating presser rolls are provided for pressing the cemented lips together as the lips are fed between the rolls after first having been raised and turned backwardly toward each other by suitable lip turning devices. The pressure rolls in such machines are arranged so as to engage the exposed side of each lip throughout the entire width of the lip and the degree of pressure applied to the base of each lip is fully as great as that applied to the other portions of the lips. Other types of machines have also been employed for setting the lips of insole blanks, hereinafter referred to as insoles, but invariably so far as I am aware, particular care has been taken to construct and arrange the lip-setting instrumentalities to insure the application of pressure or impact at the bases of both of the inner and outer lips. Such action, however, imposes considerable strain on the between-substance and has a tendency to weaken it, particularly when stock of inferior quality is being operated upon.

Accordingly, one object of the present invention is to provide improved means for performing a lip-setting operation upon a double-lipped insole without imposing undue strain upon the between-substance and thus to avoid possible weakening of the between-substance and consequent impairing of the strength of the sewing rib.

To the accomplishment of this object a feature of the invention consists in the provision, in a sole fitting machine, of lip setting devices having opposed surfaces constructed and arranged to engage the lips of a double-lipped insole throughout the upper portions only of the lips, and actuating means for causing said devices to apply pressure to the upper portions only of the lips to set the lips in raised position without compressing the lowermost portions of the lips and thereby disturbing or weakening the between-substance. In the preferred embodiment of the invention herein illustrated, the lip-setting means comprises outer and inner lip-setting members or hammers which are adapted to engage the outer and inner lips respectively, and which cooperate progressively to press the lips together and to set them in the desired upstanding position. To this end, both lip-setting members are continuously reciprocated, said members being operated simultaneously in opposite directions and cooperating to compress the insole lips between them and then to release the lips so that the insole may be advanced relatively to the lip-setting members. To insure against possibility of weakening the between-substance by pressure applied to the bases of the lips, in accordance with the feature of the invention above referred to, the work-engaging face of one of the lip-setting members is shaped so that the lower margin of the lip will not be engaged by said member and consequently the between-substance will not be compressed or disturbed as the said members cooperate upon the lip. Preferably, and as illustrated, this result is attained by shaping the outer lip-setting member or hammer to engage the upper portion only of the outer lip so that the between-substance will not be disturbed by the cooperative action of said outer and

inner members even though the inner member is adapted to engage the inner lip throughout the entire width of the latter.

In the illustrated embodiment of the invention the work is supported upon a freely rotatable disk-like work table and is fed over the table by means of a driven feed wheel arranged so that its periphery will engage the upper face of the feather of the insole, the work table supporting the feather and being spring-pressed upwardly so that the feather is yieldingly gripped between the table and the driven feed wheel.

It is desirable that the feather shall be bent backwardly somewhat from the channeled face of the insole to insure that the feather will not interfere with the passage of the circular needle through the sewing rib during the inseam sewing operation in the welt sewing machine and also for the purpose of "dishing" the unlined face of the insole so that the insole will fit better upon the last. For the purpose of bending backwardly the feather of the insole, and in accordance with another feature of the invention, the margin of the upper face of the work table is somewhat beveled or convexed transversely and the periphery of the feed wheel is correspondingly beveled or concaved transversely so that its transverse contour is complementary to that of the marginal portion of the work table. Preferably the feed disk is arranged to engage the feather throughout the entire width of the latter so as to insure the formation of a sharply defined angle at the junction of the feather with the outside lip.

To insure that the feed of the sole shall not be appreciably interrupted each time the lip-setting members move into pressing engagement with the lips, said members, in accordance with a further feature of the invention, are moved through paths inclined or oblique to the faces of the lips. As shown, the paths of the lip setting members are also inclined toward the direction of feed of the sole so that at each operative stroke, the lip-setting members have a component of movement in the direction of feed. In carrying out this feature, the angle of the stroke of the lip-setting members is so calculated that the feed of the sole is not appreciably retarded by the repeated engagements of said members with the lips.

Other features of the invention relate to the provision of means for automatically slowing down or arresting the operation of the machine when the work table is depressed to facilitate the removal of a piece of work or the introduction of a new piece of work into the machine, and to the provision of means whereby the rate of feed of the work may be varied or the feed arrested at the will of the operator, irrespective of the vertical position of the feed table.

The invention will best be understood from

a description of the preferred embodiment thereof, illustrated in the accompanying drawings, in which:—

Fig. 1 is a perspective view, partially broken away, of the head of a machine constructed in accordance with the present invention;

Fig. 2 is a perspective view, partially broken away, showing particularly the treadles and associated mechanism for raising and lowering the work table and for starting and stopping the machine and varying the rate of feed;

Fig. 3 is a view, partially in side elevation and partially in section, showing the work supporting and feeding means, and the lip-setting devices;

Fig. 4 is a detail view, on an enlarged scale, of the operating instrumentalities, illustrating the manner in which they operate upon the work;

Fig. 5 is a fragmentary view, partially in plan and partially in section, showing the work-feeding and lip-setting instrumentalities and part of the actuating mechanism for the latter; and

Fig. 6 is a detail elevational view showing part of the actuating mechanism for the inner lip-setting member.

Referring to the accompanying drawings, the work engaging instrumentalities of the machine therein illustrated comprise a freely rotatable circular work or feed table 10, a driven feed wheel 12 arranged to engage the feather of an insole S and to cooperate with the feed table 10 to feed the insole, a reciprocating outer lip-setting member or hammer 14 for engaging the outer lip, and a reciprocating inner lip-setting member or hammer 16 for engaging the inner lip of the insole, said members being moved simultaneously in opposite directions and being arranged to cooperate with each other progressively to raise the lips and turn them back against each other as the sole is fed and to compress the lips after they have been turned back so as to set them in upturned position.

The above-mentioned operating instrumentalities are mounted upon a head 18 adapted to be supported upon a bench or pedestal. The feeding devices are driven from a main shaft 20 and the lip-setting devices are driven from a counter shaft 22, said shafts being journaled in horizontal bearings carried by the head 18. The main shaft 20 is provided with a low-speed pulley 24 and a high-speed pulley 26, said pulleys being rotatably mounted in spaced relation upon the shaft and adapted to be connected, by separate belts 28 and 30, with a suitable source of power. The shaft 22 carries at one end a pulley 32 which may be driven by means of the belt 30 or by means of a separate belt as may be found most desirable. The pulleys 24 and 26 carry, at their proximate sides, driving clutch members 34

and 36, respectively, made in the form of frusto-conical shells and disposed in coaxial relation to the shaft 20. Splined to the shaft 20, between the driving clutch members 34 and 36, is a driven clutch member 38 having, at opposite sides thereof, inclined annular clutch faces 40 and 42 for cooperation with the inner faces of the hollow clutch members 34 and 36, respectively. The driven clutch member 38 is slidable axially on the shaft 20 in one direction to retract the clutch face 40 from the clutch member 34 and to engage the clutch face 42 with the clutch member 36 so as to transmit rotation at high speed to the main shaft. The clutch member 38 is slideable in the opposite direction to reverse the above described relation of the driven and driving clutch members, thereby connecting the main shaft with the low-speed pulley 24. The driven clutch member 38 is also adapted to be moved into an intermediate or neutral position to enable the operation of the machine to be completely arrested if desired.

The feed table 10 is in the form of a disk having the margin of its upper face somewhat convexly curved transversely of its periphery as indicated at 46 for the purpose of imparting a corresponding transverse curvature to the margin or feather of an insole. The table 10 is provided with a depending stem 48 which is journaled in bearings 50 and 52. The bearing 50 is fixed to the head 18 and the stem of the feed table is slideable vertically in said bearing. The bearing 52 is separated from the feed table by means of a thrust collar 54 and is carried by a slide 56 which is movable in a vertical guideway 58 (Fig. 2) carried by the head 18, this construction enabling the table to be raised and lowered for the purpose of adjusting it to operate upon work of different thicknesses. The slide 56 is provided with a vertically elongated slot 59 to avoid interference with the main shaft 20.

The table is pressed upwardly toward the feed wheel 12 by means of a coiled spring 60 which surrounds the stem 48, the lower end of the spring bearing against a collar 62 while the upper end of the spring engages a thrust collar 64 which is pressed upwardly by the spring against the bearing 52. The collar 62 supports the spring 60 and rests upon the opposite ends of a key 70 which extends through a vertically elongated slot 72 in the stem 48, the key being adjustable up and down in said slot to vary the tension of the spring 60 by means of a vertical adjusting screw 74 threaded within the lower extremity of the stem 48 and provided with a lock nut 76 for securing the screw in adjusted position. Upward movement of the feed table 10, under the influence of the spring 60, is limited by means of a stop screw 78 which is threaded through a portion of the head 18 and is formed with a conical end to engage a shoul-

der 80 at the upper end of the slide 56. By turning the screw 78 the upward limit of movement of the feed table may be varied.

The feed table is driven from the main shaft 20 through intermeshing beveled gears 82 and 84, the gear 82 being fast on shaft 20 and the gear 84 being connected to the stem 48 of the feed table by means of the key 70 hereinbefore mentioned. The hub of the gear 84 is slotted, as shown at 86, to receive the key 70, the slot 86 being elongated to permit the longitudinal movement of the stem 48 relatively to the gear 84.

The feed wheel 12 is formed with a periphery which is transversely concave to cooperate with the transversely convex face 46 of the feed table 10 to bend or mold backwardly the feather of the insole as the insole is being fed. The feed wheel 12 is fixed on an inclined shaft 88 journaled in the bearing 90 and connected by intermeshing beveled gears 92 with a short horizontal shaft 94 which in turn is connected through intermeshing spur gears 96 with the main shaft 20.

To enable the feed table 10 to be depressed to facilitate insertion of work between the table and feed wheel 12, the slide 56 carrying the bearing 52 is arranged to be operated by means of a foot treadle 100 (Fig. 2). To this end the treadle 100 is pivoted at 102 to a fixed bracket and is connected by means of a link 104 with a lever 106, the lever being fulcrumed upon a fixed stud 108 and its forward end being arranged to engage a shoulder 110 at the lower end of the vertical slot 59 in the slide 56. Normally the treadle 100 is held in elevated position by means of a spring 112 connecting the treadle with a portion of the head 18. By depressing the treadle 100 the slide 56, together with the bearing 52, will be moved downwardly while release of the treadle permits the table to rise until its movement is arrested either by the work or by the stop screw 78.

The driven clutch member 38 is connected with the treadle 100 by means enabling it to be moved to neutral position when the work table is lowered by depression of said treadle, the arrangement being such, however, that when the table is forced downwardly by increased thickness of the work, such movement of the table will not operate the clutch 38. To enable the clutch 38 to be operated, as above described, the hub of the low-speed pulley 24 is recessed at 114 to receive a coiled spring 116 which forces the clutch member 38 toward the high-speed pulley 26, and a pair of clutch operating fingers 118 extend axially through the hub of the high-speed pulley 26 and are arranged to bear against one side of the clutch member 38. The fingers 118 are carried by a disk 120 which encircles the main shaft 20 and is axially movable thereon. The high-speed pulley 26 is held against axial movement on the shaft 20 by means of a fixed

arm 122 bearing a tongue 124 which engages within an annular groove 126 in the hub of the pulley 26. The disk 120, together with the clutch operating fingers 118, is adapted to be moved in a direction to disengage the clutch member 38 from the driving clutch member 42, by the action of cooperating wedges 128 and 130 which are relatively arranged as best shown in Fig. 2, the wedge 128 being carried by a vertically movable slide 132, and the wedge 130 being supported upon the wedge 128 with provision for bodily movement toward and from the pulley 26. Suitable thrust washers 134 are provided between the disk 120 and the adjacent face of the wedge 130. The slide 132 is suitably guided for vertical movement and is apertured at 136 to receive the rear extremity of the lever 106, the arrangement being such that when the lever 106 is rocked by the treadle 100 so as to lower the feed table, the rear end of the lever will be lifted to operate the wedges 128 and 130 and the clutch operating fingers 118 so as to disengage the driving clutch member 38 from the driving clutch member 36 and cause member 38 to assume a neutral position between the members 36 and 34. Because of the vertical slot 59 in the slide 56, it will be apparent that downward movement of the feed table caused by an increase in the thickness of the work will not operate the lever 106 and consequently will not result in movement of the clutch member 38 and, therefore, will not operate to stop the machine.

Provision is also made whereby the driven clutch member 38 may be shifted to neutral position temporarily to stop the feed of the work, or may be moved into engagement with the low-speed driving clutch member 34 to cause the work to be fed slowly, independently of movement of the feed table. To this end, a second foot treadle, 138, is provided, this treadle being pivoted at 140 to a fixed bracket, having its rear extremity connected by a rod 142 with the slide 132. The treadle 138 carries a yielding abutment 144 adapted to engage the floor when the treadle is depressed sufficiently to shift the driven clutch member 38 into neutral position. The abutment 144 is adapted to yield to permit further depression of the foot treadle 138 to enable the driven clutch member 38 to be shifted into engagement with the low-speed driving clutch member 34. In this way a low rate of speed of the work-feeding and lip-setting instrumentalities may be effected when operating around the toe or other more or less abruptly curved portion of the sole margin, or the feed may be stopped whenever desired. Upon release of the treadle 138 the spring 116 will return the clutch member 38 into engagement with the high-speed driving clutch member 36 in which

condition it is normally maintained by said spring.

The outer lip-setting member or hammer 14 and the inner lip-setting member or hammer 16 are movable toward each other from positions at opposite sides of the line of feed of the lips of the insole for the purpose of setting the lips in upturned positions with their upper portions in face to face contact. These members 14 and 16 are shaped to raise the lips and turn them back progressively as the sole is fed. To enable the lip-setting members to perform this lip turning operation, the ends of the lips may be manually turned back and introduced in this condition between said members which will thereafter operate to turn the lips progressively as the lips pass between them. To facilitate the lip turning operation, the portions or surfaces of the lip-setting members first engaged by the lips are rounded as shown at 146 and 148 in Fig. 5.

The lip-setting hammers 14 and 16 are moved simultaneously toward the upturned lips to compress the lips between them and the inward movements of the hammers are repeated in rapid succession as the sole is fed. In order that the repeated engagements of the hammers with the lips shall not appreciably retard the feed of the sole, the hammers are reciprocated in paths inclined relatively to the lips in the direction of the feed of the sole with the result that as the hammer and the post move inwardly toward the lips, there is a component of movement in the direction of feed. Thus while the lips are being compressed between the cooperating hammers, these members move forwardly in the direction of feed a short distance, as well as inwardly toward each other, and accordingly the forward movement of the sole is not abruptly arrested by the engagement of the lip-setting members with the lips.

As shown in Figs. 1 and 5, the outer hammer 14 and the inner hammer 16 are carried by slide bars 150 and 152, respectively, which are mounted in guideways 154 and 156 supported by the head 18 and inclined so that as the hammers move inwardly toward the lips they also have a component of movement in the direction of feed. The slide bars 150 and 152 are reciprocated by means of levers 158 and 160 which are rocked by eccentrics 162 and 164 fast on suitably mounted shafts 166 and 168 to which are fixed bevel gears 170 and 172, each meshing with a driving gear 174 on the shaft 22. The constructions of the two lip-setting tool actuating mechanisms thus briefly outlined are similar and a detailed description of one of these mechanisms will suffice for both. The lever 160 is fulcrumed intermediate its ends upon a fixed pin 176 and the opposite ends of the lever are longitudinally slotted to receive slide blocks 178 and 180

180. The block 178 is pivotally connected with the laterally offset rear extremity of the slide bar 152 and the block 180 is carried by the eccentric 164. Rotation of the eccentric 164 rocks the lever 160 and reciprocates the slide bar 152 bearing the inner lip-setting hammer 16. In a similar manner the lever 158 is rocked by the eccentric 162 to reciprocate the slide bar 150 bearing the outer lip-setting hammer 14. The guideway 154 is inclined downwardly toward the sole in a plane parallel to the face of the feed wheel 12, and the guideway 156 is somewhat inclined downwardly toward its rear extremity (Fig. 1) to insure that the hammer 16 will engage the base of the inner lip which is lower than the flat or unchanneled portion of the upper face of the insole. The hammer 14 is secured to the slide bar 150 by means of a screw 182 (Fig. 5) which extends through a slot 184 in the shank of the hammer, said slot permitting adjustment of the hammer relatively to the slide bar in accordance with the thickness of the lip and the amount of pressure desired 25 to be imparted to the lip. The hammer 16 may be similarly mounted upon the respective slide bar 152. The block 178 carried by the slide bar 152 is adjustably secured to the bar by means of a screw 186 (Fig. 6) the shank of which extends through a slot 188 in the slide bar. By loosening the screw 186, the block 178 may be adjusted in the slotted end of the lever 160 to vary the length of stroke of the post. A similar adjustment may be made for varying the length of stroke of the hammer 14. The lip engaging face of the hammer 16 may be beveled, as shown at 189 in Fig. 4, the better to conform to the angle of the exposed face of the inner lip.

40 In accordance with an important feature of the present invention, provision is made for preventing injury to the between-substance from the pressure of the lip-setting instrumentalities against the lips. To this end, the lip-engaging face of the outer hammer 14 is beveled or cut away, as indicated at 190 in Fig. 4, so that the pressure will be concentrated at the upper portion of the lip. The pressure which is thus confined to the upper portions of the lips will be sufficient to set the lips in upturned position and when the sole is subsequently operated upon in the machine which applies the reinforcing fabric thereto, the lower portions of the lips will be subjected to pressure so that the lips will be pressed together throughout their full width.

Having thus described the invention, what I claim as new and desire to secure by Letters Patent of the United States is:—

60 1. In a machine of the class described, lip-setting devices having opposed surfaces constructed and arranged to engage the lips of a double-lipped insole throughout the upper portions only of the lips, and actuating means 65 for causing said devices to apply pressure to

the upper portions only of the lips to set the lips in raised position.

2. In a machine of the class described, co-operating instrumentalities for setting the lips of a double-lipped insole, and actuating mechanism therefor, said instrumentalities being movable toward each other to raise the lips of a double-lipped insole and set them in face to face contact and being shaped and arranged to apply pressure only to portions of the lips spaced from the upper surface of the sole. 70

3. In a machine of the class described, co-acting lip-setting tools for operating respectively upon the inner and outer lips of a double-lipped insole, one of said tools being shaped and operated to engage the respective lip throughout substantially only the outer half of its width, and means for operating said tools to set the lips in upturned position. 80

4. In a machine of the class described, co-acting lip-setting tools for engaging respectively the inner and outer lips of a double-lipped insole, one of said tools being constructed and arranged to avoid engagement with the lip at the level of the between substance, and means for operating said tools to set the lips in upturned position. 90

5. In a machine of the class described, lip-setting instrumentalities cooperating to compress between them and set in face to face contact the inner and outer lips of a double-lipped insole after said lips have been raised to upright position, one of said instrumentalities having a portion of its lip-engaging face cut away to avoid application of pressure to the between-substance, and means for feeding the insole past said instrumentalities. 95

6. In a machine of the class described, a member for engaging the inner upturned lip of a double-lipped insole, and a reciprocating hammer for engaging the upper portion only of the outer lip of the insole and for cooperating with said member to deliver successive pressure impacts against said upturned lips. 105

7. In a machine of the class described, a member for turning up the inner lip of a double-lipped insole and a reciprocating hammer for turning up the outer lip of the insole, said member and hammer being constructed and arranged to engage and compress the upper marginal portions only of said lips, and means for moving said member and said hammer simultaneously to set the lips in upturned position. 115

8. In a machine of the class described, a member for engaging the inner upturned lip of a double-lipped insole, a hammer for engaging the upper portion only of the outer lip of the insole, and means for reciprocating said member and hammer constructed and arranged to move said members simultaneously against opposite sides of said lips. 125

9. In a machine of the class described, a rotatable work supporting table having an an-

nular margin for engaging one side of the feather of a double-lipped insole, said margin being shaped to impart a transversely molded contour to the feather, means for driving the work table, a driven feed wheel having a marginal portion for engaging the opposite side of the feather and cooperating with said table to feed the work, the marginal portion of the feed wheel having a transverse contour complementary to that of the opposed marginal portion of said table, reciprocating lip-setting hammers constructed and arranged to engage respectively the inner and outer lips of the insole and to co-operate to set the lips in upturned positions, and means for imparting lip-setting movements to each of said hammers.

10. In a machine of the class described, the combination with lip-turning and setting instrumentalities of a driven rotatable work supporting table having a beveled margin for engaging the feather of the insole, and a driven feed wheel for engaging the opposite side of the feather and cooperating with the work supporting table to feed the work, said feed wheel having a beveled face complementary to the beveled face of said table for co-operating with the latter to bend backwardly the feather of the insole.

11. In a machine of the class described, means for continuously feeding a lipped insole and turning up the lip thereof, and reciprocating members movable simultaneously toward the upturned lip of the insole through paths inclined toward the direction of feed to set the lip in upturned position without appreciably interfering with continuity of the feed.

12. In a machine of the class described, means for continuously feeding a lipped sole, and reciprocating members movable simultaneously toward the upturned lip of an insole fed past said members, the paths of said members being inclined toward the direction of feed of the work to set the lip in upturned position without appreciably interfering with a continuous advancing movement of the sole while said members are operating.

13. In a machine of the class described, means for feeding a double-lipped insole, and cooperating lip-setting members arranged to engage respectively the inner and outer lips of the insole as it is being fed, said members being movable through paths inclined in the direction of feed of the insole to enable the lip-setting operation to be effected without substantial interference with the feed of the insole.

14. In a machine of the class described, means for continuously feeding a double-lipped insole, a reciprocating member for engaging the outer face of the outer lip, a second reciprocating member for engaging the inner face of the inner lip and cooperating with the first member to set the lips in upturned posi-

tion, and guideways for said reciprocating members inclined toward the direction of feed of the insole to impart to said members a component of movement in the direction of feed as the members move toward the lips of the insole.

15. In a machine of the class described, means for continuously feeding a double-lipped insole, a reciprocating member for engaging the outer face of the outer lip, a second reciprocating member for engaging the inner face of the inner lip, and means for operating said members simultaneously in opposite directions to impart repeated pressure impacts against the lips to compress the lips between them, said members being movable in paths inclined in the direction of feed so that the compression of the lips will not materially retard the feed of the insole.

16. In a machine of the class described, a support for engaging the unlipped face of a lipped sole, a reciprocating member arranged to engage the inner side of the lip and movable toward the lip in a path inclined to the direction of feed to set the lip in upturned position and also movable toward said support as it moves toward the lip, and a rounded surface on said member shaped to raise the lip and turn it progressively as the sole is moved past said member.

17. In a machine of the class described, a table for supporting a lipped insole resting with its unlipped face on the table, and a reciprocating member movable toward the inner face of the lip and downwardly toward the table and having a surface inclined relatively to the direction of movement of said member for engaging the lip to set it in upturned position substantially at right angles to the face of the sole.

18. In a machine of the class described, a rotatable table for supporting a double-lipped insole, means cooperating with said table to feed the insole and compress the feather, and reciprocating members each movable toward and from the lips, said members cooperating to turn back the lips and to set them in upturned position substantially perpendicular to the face of the sole, both of said members being movable also in paths inclined downwardly relatively to the plane of the insole.

19. In a machine of the class described, means for supporting a lipped sole while it is being fed through the machine, and a reciprocating member movable transversely to the length of the lip to set the lip in upturned position and movable in a path inclined in the direction of feed of the sole as said member moves toward the lip.

20. In a machine of the class described, means for supporting and feeding a lipped sole, and a reciprocating member movable transversely to the length of the lip to set the lip in upturned position, said member

having a component of movement in the direction of feed of the sole as it moves inwardly toward the lip.

21. In a machine of the class described, means for supporting and feeding a lipped sole, and members movable transversely to the length of the lip at opposite sides thereof and cooperating to set the lip in upturned position, said members being movable in paths inclined in the direction of feed of the sole as they move inwardly toward the lip.

22. In a machine of the class described, a rotatable table for supporting a double-lipped insole, means cooperating with said table to feed the insole and compress the feather, and reciprocating members movable transversely of the length of the lips and cooperating to set the lips in upturned position, both of said members being movable also in paths inclined in the direction of feed of the insole as they move downwardly relatively to the plane of the insole.

23. In a machine of the class described, means for feeding a lipped sole, lip-setting members located at opposite sides of the lip of the sole, and means for repeatedly moving said members through paths inclined relatively to the length of the lip in the direction of feed into positions to set the lip in turned back relation to the sole.

24. In a machine of the class described, lip-setting members slidably mounted and adapted to engage opposite sides of the lip of a sole, and means for sliding said members inwardly to set the lip in upturned position, said members having their lip-engaging faces shaped to enable the members to raise and turn back the lip as the sole is fed.

25. In a machine of the class described, means for supporting and feeding a lipped sole, and members movable transversely of the length of the lips and cooperating to set the lips in upturned position, both of said members being movable in paths inclined both downwardly and in the direction of feed of the sole.

26. In a machine of the class described, means for operating upon a lipped insole to set the lip in upturned position, cooperating feed members mounted for relative movement into and out of work feeding relation, driving mechanism normally connected to actuate said operating means, means for relatively moving the feed members out of feeding relation, and mechanism for disconnecting the driving mechanism from the feed members when said last-named means is operated.

27. In a machine of the class described, means for operating upon a lipped insole to set the lip in upturned position, cooperating feed members mounted for relative movement into and out of work feeding relation, driving mechanism normally connected with the feeding members, means for relatively

moving the feed members out of feeding relation, and mechanism for disconnecting the driving mechanism from the feed members when said last-named means is operated.

28. In a machine of the class described, means for operating upon a lipped insole to set the lip in upturned position, cooperating feed members mounted for relative movement into and out of work feeding relation, driving mechanism normally connected with the lip-setting means and the feed members, means for relatively moving the feed members out of work feeding relation, and mechanism for disconnecting the driving mechanism from the feed members when said last-named means is operated.

29. In a machine of the class described, means for operating upon a lipped insole to set the lip in upturned position, cooperating feed members mounted for relative movement into and out of work feeding relation, driving mechanism normally connected with the lip-setting means and the feed members, means for relatively moving the feed members out of work feeding relation, and mechanism for disconnecting the driving mechanism from the feed members when said last-named means is operated and also at other times under the control of the operator.

30. In a machine of the class described, an instrumentality for operating upon a sole, cooperating feed devices arranged to engage opposite sides of the sole and mounted for relative movement into and out of feeding relation, variable speed driving mechanism normally connected to actuate said feed devices, means for relatively moving said feed devices out of feeding relation, connections between said means and said driving mechanism for disconnecting the driving mechanism from the feed devices when said means is operated, and means acting through said connections to operate said driving mechanism to vary the rate of feed at the will of the operator.

31. In a machine of the class described, means for operating upon a lipped insole to set the lip in upturned position, a rotatable work table capable of being raised and lowered, a feed device arranged to cooperate with the work table when the latter is in raised position to feed the work, means under the control of the operator for raising and lowering the work table, a two-speed driving mechanism, and means for connecting said mechanism with the feed device when the table is raised and disconnecting it from the feed device when the table is lowered.

32. In a machine of the class described, means for operating upon a lipped insole to set the lip in upturned position, a rotatable work table capable of being raised and lowered, a feed device arranged to cooperate with the work table when the latter is in raised position to feed the work, means under

the control of the operator for raising and lowering the work table, a two-speed driving mechanism, and means for connecting said mechanism with the lip-setting means when the table is raised and disconnecting said mechanism from the lip-setting means when the table is lowered.

33. In a machine of the class described, a tool for operating upon a piece of work, a vertically movable work table, means for raising and lowering the table, means for cooperating with said table to feed the work, means for raising the table into position for the work to be fed and operated upon by said tool, a shaft, a constantly rotating driving clutch member mounted to turn freely on said shaft, a driven clutch member splined on said shaft and normally held in engagement with the driving clutch member, and connections between the driven clutch member and the table for disconnecting said clutch members when the table is lowered.

34. In a machine of the class described, a tool for operating upon a piece of work, a vertically movable work table, means for raising and lowering the table, means for cooperating with said table to feed the work, means for raising the table into position for the work to be fed and operated upon by said tool, a shaft, a constantly rotating driving clutch member mounted to turn freely on said shaft, a driven clutch member splined on said shaft and normally held in engagement with the driving clutch member, and connections between the driven clutch member and the table for disconnecting said clutch members when the table is lowered, and means for disconnecting said clutch members independently of movement of said table.

35. In a machine of the class described, a tool for operating upon a piece of work, a vertically movable work table, means for raising and lowering the table, means for cooperating with said table to feed the work, means for raising the table into position for the work to be fed and operated upon by said tool, a shaft, high and low speed driving clutch members mounted to turn freely on said shaft, a driven clutch member splined on said shaft between the driving clutch members and normally connecting the high speed clutch member with the shaft, a device for shifting the driven clutch member, means for operating said shifting device to disconnect the high speed clutch member from the shaft when the table is lowered, and means for operating said shifting device independently of movement of the table for disconnecting the high speed clutch member from the shaft.

36. In a machine of the class described, a tool for operating upon a piece of work, a vertically movable work table, means for raising and lowering the table, means for cooperating with said table to feed the work,

means for raising the table into position for the work to be fed and operated upon by said tool, a shaft, high and low speed driving clutch members mounted to turn freely on said shaft, a driven clutch member splined on said shaft between the driving clutch members and normally connecting the high speed clutch member with the shaft, a device for shifting the driven clutch member, means for operating said shifting device to disconnect the high speed clutch member from the shaft when the table is lowered, and auxiliary means for operating said shifting device to connect the low speed clutch member with the shaft.

37. In a machine of the class described, a tool for operating upon a piece of work, a vertically movable work table, means for raising and lowering the table, means for cooperating with said table to feed the work, means for raising the table into position for the work to be fed and operated upon by said tool, a shaft, high and low speed driving clutch members mounted to turn freely on said shaft, a driven clutch member splined on said shaft between the driving clutch members and normally connecting the high speed clutch member with the shaft, a device for shifting the driven clutch member, and a foot treadle connected with said shifting device and movable to one position to disconnect the high speed clutch member from the shaft and to another position to connect the low speed clutch member with the shaft.

In testimony whereof I have signed my name to this specification.

WALTER D. SHAFFER.
